Attorneys

UNITED STATES PATENT OFFICE.

HARRY A. TIEMANN, OF FORT COLLINS, COLORADO.

BUCKLE.

Application filed June 7, 1923. Serial No. 644,017.

To all whom it may concern:

Be it known that I, HARRY A. TIEMANN, a citizen of the United States, residing at Fort Collins, in the county of Larimer and State of Colorado, have invented certain new and useful Improvements in Buckles, of which the following is a specification.

This invention relates to buckles of the one-piece clamping type.

The object of the invention is to produce a buckle of attractive appearance which can be stamped out in one piece from sheet metal and which will combine moderate cost with durability, certainty of clamping action, and ease of manipulation.

The general principles of the invention can be best explained after describing in detail the preferred embodiment of the invention which is illustrated in the accompanying drawing.

In this drawing:

Fig. 1 is a front elevation of the buckle;

Fig. 2 is a section on the line 2—2 of Fig. 1;

Fig. 3 is a section on the line 3—3 of Fig. 1;

Fig. 4 is a section on the line 4—4 of Fig. 1;

Fig. 5 is a front elevation showing the buckle mounted on a belt or strap, a part of the latter being broken away to illustrate the engagement of the strap with parts of the buckle;

Fig. 6 is a section on the line 6—6 of Fig. 5;

Fig. 7 is a section on the line 7—7 of Fig. 6 and

Fig. 8 is a perspective view of the buckle.

The buckle consists of a marginal frame 10 whose outer contour is shown as rectangular but may assume any form, and whose inner contour is preferably rectangular as shown, though it may depart somewhat from this form provided requirements hereinafter specified are met.

Formed integrally with the marginal frame 10 are two cross bars or members 11 and 12; the member 12 being preferably, but not necessarily, formed with an extension 13 intended to engage a retaining loop on the clothes of the wearer when the buckle is used as a belt buckle. This loop is indicated with dotted lines at 14 in Fig. 5. The extension 13 is preferably formed with an

enlargement or head 15 to maintain engagement with the loop 14.

As clearly shown in Figs. 5 and 6, the cross bar 12 forms the means of attachment of the buckle to the belt or strap 16 with which it is used. The strap is formed with an aperture or slot 17 through which the projection 13 is inserted and the end of the strap beyond this aperture is bent back and stitched or otherwise connected to the main portion of the strap as indicated at 18 in Fig. 6.

The end of the marginal frame 10, adjacent the cross bar 12, serves as a keeper for the free end of the strap and for purposes of description this end of the buckle will hereafter be referred to as the "keeper end" of the buckle.

Inasmuch as two thicknesses of the strap pass over the cross bar 12, and then through the interval between it and the keeper end of the buckle, the bar 12 is spaced from the end member of the marginal frame 10 a correspondingly greater distance as compared with the distance between the cross bar 11 in the opposite end of the frame 10 which, for lack of a better term, will be designated as the "free end" of the buckle.

As best shown in Fig. 2, the marginal frame 10 is bowed longitudinally, its convex face being forward, and as best shown in Figs. 3 and 4, the cross bars 11 and 12 are sharply offset to the rear of the marginal frame 10 adjacent their points of junction therewith, and between such points of junction are bowed sharply forward.

The forms of the various parts above described are so coordinated that the inserted end of the strap is bowed forward, both longitudinally and transversely, between the end members of the marginal frame 10. This is clearly illustrated in Figs. 6 and 7, and serves the useful purpose of increasing greatly the frictional engagement of the inserted strap end with the cross bars 11 and 12, and with the end members of the marginal frame 10.

Furthermore, the forms of the parts are so coordinated that the pull of the permanently attached strap end on the cross bar 12 and its forward pressure toward the keeper end of the marginal frame 10 tends to swing the free end of the buckle inward or toward the body of the wearer. This

tendency is resisted by the pull of the strap end on the free end of the marginal frame and the effect is to produce a pronounced clamping action on the strap end at the 5 keeper end of the belt.

In effect, the greater clamping action is exerted at this point, and to release the free end of the belt the procedure is to draw the keeper end of the buckle forward or away 10 from the body of the wearer, permitting the strap end to be withdrawn. Accordingly, the longitudinal bowing of the marginal frame of the buckle, and the forward bowing of the cross bars are important factors 15 in securing the necessary clamping action and tests have shown that a buckle made as described above, unlike most one-piece clamping buckles, can be used with straps of decidedly different thicknesses.

20 The feature of bowing the belt both longitudinally and transversely as it passes through the buckle is therefore important from the standpoint of utility. It is also important from the aesthetic standpoint, as 25 it imparts to the buckle and strap a very attractive appearance.

While the buckle primarily is intended for use on belts and has been described in detail in that connection, I do not thereby intend to imply any limitation to that field.

30 When used as a general purpose buckle, the projection 13 with its head 15 will commonly have no function and accordingly may be omitted.

35 While I prefer the simple rectangular form of buckle illustrated, it is obvious that the external contour can be varied according to the taste of the designer.

40 The internal contour of the marginal frame should be made rectangular for best effect, but can depart somewhat from that form provided this contour and the spacing and form of the cross bars 11 and 12 be so coordinated as to produce the described 45 double flexure of the belt and the described clamping action under the keeper end of the buckle.

What is claimed is:

50 1. A buckle of the clamping type comprising in one piece an open rectangular frame, bowed longitudinally to produce a convex front face; and two cross bars spaced from the end members of said frame and substan-

tially parallel thereto, said members being offset to the rear adjacent their points of connection with the side members of the frame, and bowed forward intermediate said offsets. 55

2. A buckle of the clamping type comprising in one piece an open frame; two 60 cross bars spaced from the end members of said frame, said members being offset to the rear adjacent their points of connection with the side members of said frame and bowed forward intermediate said offsets; and a 65 projection formed with an enlarged head mounted on one of said cross bars and extending therefrom toward the middle of the buckle.

3. A one-piece clamping buckle, formed 70 with two transverse slots through which the strap to be clamped is inserted, portions of the buckle intermediate said slots being so bowed forward as to hold the overlying portion of the inserted strap bowed both longitudinally and transversely. 75

4. A buckle of the clamping type comprising in one piece an open frame and two cross bars spaced from the end members of said frame, said members being offset to the rear 80 adjacent their points of connection with the side members of the frame and bowed forward intermediate said offsets, the parts being so constructed and arranged that a strap clamped in said buckle is curved both longitudinally and transversely within the limits of the buckle frame. 85

5. A buckle of the clamping type comprising in one piece an open substantially rectangular frame, and two cross bars, one 90 of said cross bars being spaced from the free end of the buckle frame to leave a strap receiving slot, the other bar being spaced from the keeper end of the buckle to leave a keeper slot, both cross bars being offset to the rear 95 adjacent their points of connection with the buckle frame and bowed forward, intermediate such offsets, the various parts being so formed that the buckle is urged by pull of the connected strap to exert a clamping pressure on the strap where it passes under the keeper end of the buckle frame. 100

In testimony whereof I have signed my name to this specification.

HARRY A. TIEMANN.
